(57) **CLAIM**

The ornamental design for a tube cap, substantially as shown and described.

DESCRIPTION

FIG. 1 is a top view of a tube cap embodying the invention. FIG. 2 is a bottom perspective view of a tube cap embodying the invention.

FIG. 3 is a top perspective view of a tube cap embodying the invention; and,

FIG. 4 is a cross-sectional side view of a tube cap embodying the invention.

The tube cap may be constructed of colored or clear materials having visual appeal and ranging from transparent to opaque in optical transmission properties.
